UNITED STATES PATENT OFFICE

ANDREW S. KUSHNER, OF BECCARIA, PENNSYLVANIA

INVALID'S CUSPIDOR

Application filed July 1, 1930. Serial No. 465,217.

This invention relates to an improved cuspidor for use by invalids, and has more particular reference to a portable device, which may be arranged in close proximity to a bed 5 or the like, whereby to permit it to be utilized with facility and freedom by the occupant of the bed in either a reclining or sitting position.

Briefly stated, the structure is characterized by a portable stand, a two-way conduit for circulating and return of water, an adjustable support for the conduits associated with the stand, and a suitably designed and appropriately fashioned head structure, 15 against which the mouth of the patient is placed when spitting, vomiting or the like.

These specific structural details and their relative arrangement and association will become more readily apparent from the following description and drawings.

In the drawings:

Figure 1 is an elevational view of a portable cuspidor device, constructed in accordance with the present invention and showing the manner in which it is associated with a bed.

Figure 2 is a vertical sectional view on the line 2—2 of Figure 1.

Figure 3 is a top plan view of the hollow head unit.

Figures 4 and 5 are detail sections on the lines 4—4 and 5—5 respectively of Figure 3.

Figure 6 is a horizontal or longitudinal sectional view on the line 6—6 of Figure 1.

In the drawings, in Figure 1, the reference character 7 merely designates the bed which is illustrated to show the approximate disposition of the improved cuspidor structure.

The improved structure comprises a portable stand 8. This is provided with casters or rollers 9 attached to the lower ends of the supporting legs 10. The legs are fastened at their upper ends to an inverted pan-shaped top 11. This top has a central opening and associated therewith is a riveted guide block 12, of general circular configuration. This is formed with a pair of vertical guide holes, one of which serves to accommodate the cylindrical casing 13 and the other of which

50 accommodates the sleeve 14. The parts 13

and 14 are fastened together as a unit. The part 14 is open ended and held in adjusted position through the medium of the set screw 15. The part 13 is in the nature of a cylinder and held in adjusted position through the medium of the screw 16. A water supply pipe 17 constituting a part of the return portion of the conduit is mounted for adjustment in the sleeve 14. A spaced parallel pipe 18 extends slidably through the opposite capped end of the cylindrical casing 13.

That portion of the pipe within the casing is provided with a shoulder forming washer 19, against which one end of a coil spring 20 is placed. The opposite end of the spring bears against the lower cap. Hose elements 21 and 22 respectively are connected with these pipes 17 and 18 to supply and return the circulating system of water. Attached to the upper ends of the pipes 17 and 18 are horizontal branches 23 and 24, respectively, adjoined together. Each branch is formed with a terminal stuffing box 25.

The improved head unit comprises an especially designed hollow casing or bowl 26, and spaced parallel pipes 27 and 28, having their flanged inner ends mounted for telescopic sliding within the branches 23 and 24. The pipe 27 is provided with a control valve 29 and this permits the entire unit to be slid back and forth with respect to the sections 23 and 24 and also permits the circulating water to be regulated through the medium of the valve. The receptacle 26 comprises a hollow casing of semi-cylindrical cross sectional shape as represented in Figure 4, having an annular circulating channel 30 formed therein from a central over-flow depression 31, and a suitable outlet nipple 32. The numeral 33 designates the distributing head or inlet nipple which projects into the interior of the circulating receptacle. In the rim portion of the receptacle, at the front is an intake port or opening 34, forming the entrance for use by the patient.

Briefly stated, the stand 8 constitutes the primary factor of the main portable support. Likewise, the part 12 constitutes an element thereof, as well as the casing 13 and the adjusting sleeve 14. The conduit made up of

the several sections of piping and their associated details constitute a relatively movable part adjustably mounted on the stand, so that it is permitted to be regulated for vertical adjustment to arrange the receptacle 26 at the proper elevation for efficient use. In addition, this conduit and receptacle unit is turnable and the section which overlies the bed is made up of the pipes 27 and 28, and is slideable through the telescopic mounting. Hence, the device is susceptible of being arranged for convenient and efficient and expeditious usage by the occupants of the bed. Essentially, the support comprises a portable stand, and a vertical mounting (parts 13 and 14) mounted for vertical adjustment thereon. Secondly, it comprises the conduit unit, which is yieldably suspended in the mounting, as well as turnable with respect thereto. 20 The conduit is characterized by the feed and return portions which are joined through the medium of pipes 27 and 28 to the head structure, which is individualized by the presence therein of the receptacle 26. The head unit 25 is adjustable in a horizontal plane through the telescopic connections of the pipes 27 and 28, with the branches 23 and 24.

Thus the conduit embodies the intercommunicating sections for feed and return of the 30 vertical portions which are yieldably suspended in the adjustable mounting on the stand, and a structure which is extensible in a horizontal plane.

Although I have shown the preferred embodiment of my invention it is to be understood that various changes in the shape, size and arrangements of parts may be resorted to, without departing from the spirit of the invention or the scope of the appended claims.

40 What is claimed is:

1. In a structure of the class described, a wheel supported stand including a plurality of suspension legs, and a top attached to said legs, a disc-like member fastened on said top 45 and provided with vertical guide holes, and set screws projecting into said guide holes, a mounting including portions adjustable through said guide holes, and a circulating conduit embodying piping having portions 50 mounted for adjustment in said mounting, the conduit mounting being bodily adjustable as a single unit, and the conduit being individually adjustable with respect to the mounting when the latter is in fixed position 55 on said disc.

2. In a structure of the class described, a portable stand including a top, a disc mounted on said top and having a pair of vertical guide holes, and set screws projecting into said holes, a mounting embodying an open ended tube slideable in one hole, and a casing attached to said tube and slideable through the remaining hole, and a circulating device including pipes mounted for sliding adjustment in the tube and casing respectively, that pipe in said casing being formed with a stop collar, and a spring surrounding said last named pipe and engaging the collar at one end and resting at its opposite end against the upper end of the casing to yieldably suspend said circulating device in said mounting.

spectively, that pipe in the casing being formed with a stop collar, and a spring surrounding the last named pipe and engaging the collar at one end and resting at its opposite end against the adjacent end portion of the casing, so as to yieldably suspend the circulating device from said mounting. 70

3. In a structure of the class described, a stand comprising roller equipped legs and a top plate connected thereto, said top plate being formed with central openings, a disc like collar attached to said top plate and spanning said central opening, said collar being formed with a pair of vertical guide holes, set screws carried by the collar and projecting at their inner ends into said guide holes, and a conduit mounting comprising an open ended tube slideable through said one guide hole, and a closed ended cylinder attached to said tube and slideable through the remaining guide hole. 80

4. In a structure of the class described, a stand comprising roller equipped legs and a top plate connected thereto, said top plate being formed with central openings, a disc like column attached to said top plate and spanning said central opening, said collar being formed with a pair of vertical guide holes, set screws carried by the collar and projecting at their inner ends into said guide holes, and a conduit mounting comprising an open ended tube slideable through said one guide hole, and a closed ended cylinder attached to said tube and slideable through the remaining guide holes, together with spring suspension means in said cylinder for use in association with a complementary part of an adjustable water circulating conduit device. 90

5. In a structure of the class described, a stand including a top provided with guide holes, a mounting embodying an open-ended tube slideable in one hole and a casing attached to said tube and slideable through the remaining holes, and a circulating device including pipes mounted for sliding adjustment in the tube and casing respectively, that pipe in said casing being formed with a stop collar, and a spring surrounding said last named pipe and engaging the collar at one end and resting at its opposite end against the upper end of the casing to yieldably suspend said circulating device in said mounting. 100

In testimony whereof I affix my signature.

ANDREW S. KUSHNER.
